Inventor:

UNITED STATES PATENT OFFICE.

WILLIAM FREDERICK STEPHAN, JOHN A. STEPHAN, AND FREDERICK DANIEL STEPHAN, OF SHELBYVILLE, INDIANA.

BOOT AND SHOE.

1,400,836.

Specification of Letters Patent. Patented Dec. 20, 1921.

Application filed July 5, 1917. Serial No. 176,841.

To all whom it may concern:

Be it known that we, WILLIAM FREDERICK STEPHAN, JOHN A. STEPHAN, and FREDERICK DANIEL STEPHAN, citizens of the United

5 States, residing at Shelbyville, in the county of Shelby and State of Indiana, have invented certain new and useful Improvements in Boots and Shoes, of which the following is a specification, reference being had therein

10 to the accompanying drawing.

This invention relates to improvements in boots and shoes, and more especially to improved heel fastening means.

The object of the invention is to provide 15 improved heel fastening means that will securely clamp the upper to the heel without tearing or marring the upper, and will afford a very firm connection of these parts.

A further object of the invention is to provide 20 improved heel fastening means that can be very quickly and easily applied, that can be employed with various types of shoes and is adapted for use in repair work as well as in the manufacture of shoes.

25 The invention, with other objects and advantages thereof, and the particular construction, combination and arrangement of parts comprising the same will be understood from the following detailed description 30 when considered in connection with the accompanying drawings, forming part hereof and illustrating one embodiment of the invention.

In the drawings:

35 Figure 1 is a side elevation of a shoe with parts shown in section having heel fastening means constructed in accordance with the present invention.

Fig. 2 is a section on the line 2—2 of 40 Fig. 1, and

Fig. 3 is a detailed perspective view of the clamping plate.

It will be understood that while we have, by way of example, illustrated in the drawings a particular embodiment of the invention, the invention can take other forms, and variations and minor changes in the particular construction shown, as will appear to those skilled in the art, may be made without departing from the spirit of the invention.

Referring to a detailed description of the drawings, wherein like reference characters 55 designate corresponding parts throughout the several views, the special construction of

heel fastening means shown comprises a plate 1 of the general outline of the upper face of the heel 2 of the shoe and having a depending flange 3 at the sides and back thereof. The plate is relatively thin and 60 constructed of metal, preferably thin spring steel. The plate is adapted to be positioned within the shoe to overlie the rear part of the inner sole 4 with its depending flange 3 fitting over the side and rear edge portions of the inner sole. Means is provided for connecting the plate 1 with the heel 2 so that the outer side and back marginal portions of the plate and the adjoining flange exert a downward pressure directly upon the 70 edge portions of the inner sole 4 and securely bind the upper 5 to the edge portion of the heel. A fastening member 7 is provided for this purpose and said member preferably takes the form of an ordinary screw, as 75 shown. The plate 1 is provided with a countersunk opening 7' at the central part thereof to receive the head of the fastening member 7, the shank of the screw or fastening member extending through the opening in 80 the plate, through the inner sole 4, and the adjacent filler elements therebelow, and entering the body of the heel 2 at the central part thereof. Normally the major portion of the plate extends in a flat position. When 85 the fastening member 7 is tightly screwed down into the heel the plate 1 is flexed, the central portion of the plate being pulled down and caused to assume the shape of the heel, at the same time pressure is applied 90 all around the side and back marginal portions of the plate, the edge portion of the inner sole being pressed down against the upper, and the upper being tightly clamped to the heel. The particular form of fastening member shown in the present instance is of a special advantage when wooden heels are employed, such as the heel 2 illustrated in the drawings. It will of course be understood that when heels of other material are 100 used, other forms of fastening means to suit the different conditions may be employed. In the construction illustrated in full lines in Fig. 3 of the drawings the depending flange is shown as continuous. In this figure is indicated in dotted lines a slightly modified construction in which the depending flange 105 is made up of sections.

It will be noted that the clamping pressure of the plate is applied uniformly to the 110

upper indirectly through the inner sole, so that the clamping plate will not tear or mar the upper.

It will also be observed that the clamping means can be applied very quickly and easily, and that the same is adapted for use with various styles of shoes. In practice it is intended to manufacture the plates in different sizes to suit various sized shoes, and the heel fastening means can be advantageously employed in repair work.

What we claim is:

1. A shoe having on its heel seat a metallic plate provided on its edge with a depending flange and secured to the heel for the purpose described, said depending flange tapering from the back of the heel toward the forward edge of the plate.
2. A shoe having on its heel seat a metallic plate provided on its edge with depending portions and secured to the heel for the purpose described, said depending portions being deepest at the back of the heel and decreasing in depth toward the forward edge of the plate.
3. A shoe having on its heel seat a metallic

plate provided on its edge with depending portions and secured to the heel for the purpose described, said depending portions being deepest at the back of the heel and decreasing in depth toward the forward edge of the plate, the plate being of a length to extend substantially beyond the forward edge of the heel.

4. A shoe having on its heel seat a metallic plate provided around its rear and the greater portion of its side edges with a depending flange and secured to the heel for the purpose described, said depending flange tapering from the rear of the heel toward the forward edge of the plate, and the plate being of a length to extend substantially beyond the breast of the heel.

In testimony whereof we hereunto affix our signatures in the presence of two witnesses.

WILLIAM FREDERICK STEPHAN.
JOHN A. STEPHAN.
FREDERICK DANIEL STEPHAN.
